UNITED STATES PATENT OFFICE

HANS GÄBLER, OF HELMSTEDT, GERMANY, ASSIGNOR TO WEBER & SEELÄNDER,
MASCHINENFABRIK, OF HELMSTEDT, GERMANY

RUBBING MILL

Application filed December 4, 1929, Serial No. 411,630, and in Germany December 1, 1928.

My invention relates to improvements in rubbing mills, and more particularly in mills designed for rubbing and mixing material such as soap, and comprising a plurality of rolls in rubbing engagement with one another. The object of the improvements is to provide a mill by means of which the material is sufficiently refined and intermittently mixed by once passing through the mill, and in which neither the rolls nor the material are materially heated, the said rolls being rotated at low circumferential velocity. With this object in view my invention consists in providing a pair of rolls of large diameter rolling in contact with each other and at different circumferential velocities, each roll being in rolling engagement with a plurality of rolls of comparatively small diameter, the small rolls cooperating with the large roll of smaller circumferential velocity having a smaller circumferential velocity than the cooperating large roll, and the small rolls cooperating with the large roll of greater circumferential velocity having a greater circumferential velocity than the cooperating large roll. Between successive small rolls scrapers are provided which bear on the surfaces of the large or small rolls and scrape the material therefrom after each rubbing operation and allow the same to drop into boxes in which the rubbed and scraped materials are mixed, and from which it is supplied to the next rubbing position.

For the purpose of explaining the invention an example embodying the same has been illustrated in the accompanying drawings showing a diagrammatical elevation of the mill.

Fig. I is a vertical section of the entire mill; Fig. II is a plan view.

In the example shown in the drawings the mill comprises rolls o^1 and o^5 of large and equal diameters having fixed bearings, and the said rolls are provided with driving mechanisms imparting a greater circumferential velocity v^5 to the roll o^5 than to the roll o^1 the circumferential velocity of which is v^1 . The roll o^1 of smaller circumferential velocity is in rolling engagement with three circumferentially shiftably mounted rolls o^2 ,

o^3 , o^4 having equal circumferential velocities v^2 , v^3 , v^4 , the said circumferential velocities v^2 , v^3 , v^4 being smaller than the circumferential velocity v^1 of the roll o^1 . The large roll o^5 is in rolling engagement with four small rolls o^6 , o^7 , o^8 , o^9 , the circumferential velocities v^6 , v^7 , v^8 , v^9 of which are either equal or substantially equal and greater than the circumferential velocity v^5 of the large roll o^5 . The material to be rubbed is supplied through a funnel a , and between the successive rolls of small diameter there are scrapers b^1 , b^2 , b^3 , b^4 , b^5 and hoppers a^1 , a^2 , a^3 , a^4 , a^5 for collecting the scraped material and supplying the same to the next pair of rolls. The scrapers b^1 and b^2 engage the roll o^1 , and the scrapers b^3 , b^4 , b^5 engage the small rolls o^6 , o^7 , o^8 .

In the operation of the mill the material is taken into the funnel a , and it is supplied therefrom to the rolls which successively rub the same at the points 1 to 8.

After passing a pair of rubbing rolls the material is scraped by the scrapers b^1 to b^5 and dropped into the boxes a^1 to a^5 before being supplied to the next pair of rubbing rolls. Within the said hoppers the partly rubbed material is intimately mixed. Finally a scraper c removes the material from the last roll o^9 . I have found that by once passing the material through the mill it is thoroughly rubbed and intimately mixed.

I claim:

1. In a mill for mixing plastic material, a pair of coaxial large rolls arranged with their axes at different vertical levels, the upper roll having a higher peripheral speed than the lower, a series of small rolls engaging the upper large roll and driven faster than said roll, a series of small rolls engaging the lower large roll and driven more slowly than said roll, hoppers between pairs of small rolls of the lower series for feeding material to a mixing point, means acting on the lower large roll adjacent each hopper for removing the plastic material therefrom and depositing it in said adjacent hopper, hoppers between pairs of small rolls of the upper series for feeding material to a mixing point, and means adjacent the respective hoppers

acting on the small rolls for removing the material therefrom and depositing it in said respective hoppers.

2. In a mill for mixing plastic material, the combination of a pair of coacting rolls of relatively large diameter having their axes spaced vertically, the upper roll having greater speed than the lower, a series of small rolls engaging the upper roll and having greater peripheral velocity than the coacting large roll, a series of small rolls engaging the lower large roll and having smaller peripheral speed than the coacting large roll, means for feeding material to the lower large roll, hoppers between successive pairs of small rolls for feeding material to the next mixing point, and means adjacent each hopper for removing material from a roll for feeding said material to the adjacent hopper.
3. In a mill for mixing plastic material, the combination of a pair of coacting rolls of relatively large diameter having their axes spaced vertically, the upper roll having greater speed than the lower, a series of small rolls engaging the upper roll and having greater peripheral velocity than the coacting large roll, a series of small rolls engaging the lower large roll and having smaller peripheral speed than the coacting large roll, means for feeding material to the lower large roll, and scraping means acting on a roll after each mixing operation said scraping means projecting the material toward the next mixing point, the last scraping means projecting the mixed material out of the machine.

In testimony whereof I have affixed my signature.

HANS GÄBLER.
